(57) **CLAIM**

The ornamental design for a beverage brewing device, as shown and described.

DESCRIPTION

FIG. 1 is a top perspective view of a beverage brewing device according to our new design;

FIG. 2 is a bottom perspective view of the beverage brewing device of FIG. 1;

FIG. 3 is a front elevational view of the beverage brewing device of FIG. 1;

FIG. 4 is a side elevational view of the beverage brewing device of FIG. 1;

FIG. 5 is a rear elevational view of the beverage brewing device of FIG. 1;

FIG. 6 is a top plan view of the beverage brewing device of FIG. 1; and,

FIG. 7 is a bottom plan view of the beverage brewing device of FIG. 1.

The broken lines in the drawings are included for the purpose of illustration and form no part of the claimed design.
